CLAIM

The ornamental design for a nightlight, as shown and described.

DESCRIPTION

FIG. 1 is front right isometric perspective view of a new ornamental design for a nightlight;

FIG. 2 is a front elevation view of the nightlight of FIG. 1; FIG. 3 is a rear elevation view of the nightlight of FIG. 1; and,

FIG. 4 is a right side elevation view of the nightlight of FIG. 1, the left side elevation view being a mirror image thereof. The broken lines shown represent unclaimed subject matter and form no part of the claimed design.
